UNITED STATES PATENT OFFICE.

JOSEPH JOULE AND CHARLES ALBERT COUPS, OF BELLEVILLE, NEW JERSEY,
ASSIGNORS TO EASTWOOD WIRE MANUFACTURING COMPANY, OF BELLE-
VILLE, NEW JERSEY, A CORPORATION OF NEW JERSEY.

LOOM.

1,353,962.

Specification of Letters Patent. Patented Sept. 28, 1920.

Application filed March 10, 1916. Serial No. 83,221.

To all whom it may concern:

Be it known that we, JOSEPH JOULE, a citizen of the United States, and a resident of Belleville, in the county of Essex and

5 State of New Jersey, and CHARLES ALBERT COUPS, a subject of the King of Great Britain, and a resident of Belleville, in the county of Essex and State of New Jersey, have jointly invented certain new and use-
10 ful Improvements in Looms, of which the following is a specification.

The invention pertains more particularly to improvements in the lay and means connected or associated therewith for imparting motion thereto for making the beats, the lay preferably forming a so-called long beat and a short beat at each operation. We illustrate our invention as embodied in a loom for weaving wire cloth of the char-
20 acter required for use in paper making ma-
chines, this wire cloth being of very fine mesh and requiring the utmost uniformity throughout its extent.

The loom illustrated in the drawings pre-
25 sent some well-known features, these being the warp beam, breast beam and cloth beam, and also the lay beam frame with the exception of the features provided thereon for carrying out the present invention.

30 In accordance with our invention we provide spring-actuated means co-acting with cams on the lay beam frame for causing the lay beam to make its beats against the weft, and we also provide cam-controlled means
35 for returning the lay beam frame to its initial or rear position and permitting said frame to move forwardly at the proper periods for making the beats. Our invention thus pertains more particularly to the
40 lay motion or means for operating and controlling the lay beam frame, and this invention will be fully understood from the detailed description hereinafter presented, reference being had to the accompanying draw-
45 ings, in which:

Figure 1 is a substantially central vertical section through a loom equipped with the features of our invention but otherwise of known construction;

50 Fig. 2 is a horizontal section on an enlarged scale through a portion of the same taken on the dotted line 2-2 of Fig. 1;

Fig. 3 is a horizontal section, partly broken away, through a portion of the same
55 taken on the dotted line 3-3 of Fig. 1;

Fig. 4 is a rear end view, partly broken away, of a portion of the loom, the features shown in Fig. 4 being the lever arm and cam by which the operation of the lay is controlled, and

60 Fig. 5 is a front elevation, partly broken away, of a portion of the loom, the feature more particularly presented in Fig. 5 being one of the bell-crank levers which is normally held spring-pressed against the lay or a cam thereon and serves under the influence of the spring to cause the lay to perform its beats.

65 In the drawings 10 designates the usual corresponding side supporting frames for the loom parts; 11 the customary warp beam; 12 the breast beam; 13 the cloth beam; 14 the lay beam frame comprising the vertical side portions 15 and connecting transverse beam 16, and 17 a transverse beam affording a tramway for a magnetic shuttle carriage 18 of known type, all of the features just mentioned being well-known in this art with the exception of certain cams
70 19 which, in accordance with our invention, we secure to the side members 15 of the lay beam frame 14. 20 denotes the usual warp strands or wires.

75 21 designates the driving shaft upon one end of which is mounted a belt wheel 22 to be driven by a belt, not shown, as usual. The driving shaft 21 is connected with and actuates an auxiliary shaft 23 through the medium of the pinion wheel 24 and gear wheel 25, and the timing of the rotation of the shaft 23 with the shaft 21 is automatically controlled in an entirely well-known manner by an automatic clutch 26 by which the gear wheel 25 becomes keyed to the shaft 23. There are moments when the shaft 23
80 should remain at rest, as we hereinafter explain, and hence the clutch 26 is provided so that while the gear wheel 25 may have a continuous motion the shaft 23 may in its movements be timed in accordance with the requirements of the loom.

85 Automatic clutch control mechanism suitable for use in the loom herein presented is disclosed in Letters Patent No. 779,025 and 779,395, both dated January 3, 1905, to the loom described in which Letters Patent our invention has been produced as an addition or improvement.

90 Upon the shaft 23 is secured a cam 27 having an extended arc surface 28, a pro-
95

105

110

jection 29 and depressions 30, 31 at opposite sides of said projection. The cam 27 will rotate with the shaft 23, and the shape of the periphery of said cam permits, through the intermediate connection presently to be described, the lay to perform its two beats, the long beat and the short beat, at each operation and then be returned to its rear position shown in Fig. 1.

10 In rear of the cam 27 is provided a lever 32 composed of two corresponding arms or members 33 between which and in alignment with the cam 27 is mounted on a bolt or pin 34 a smooth surfaced wheel 35 which engages the periphery of the cam 27. The lower ends of the members 33 of the lever arm 32 are pivotally mounted by means of a bolt or the like 36 in a bracket 37 fastened to the floor or other suitable support. The 15 members 33 of the lever arm 32 have secured between their upper ends a sleeve 38 to which the rear end of the pitman rod 39 is secured, the forward end of said rod 39 being pivotally connected with ears 40 extending downwardly from the lower middle portion of the lay beam frame 14. The cam 27, lever arm 32, and connecting rod 39 are made use of to return the lay beam frame 14 to its rear position and to time its movements forwardly to make the beat under the action of the springs 41 whose tension retains the roller 35 carried by the lever arm 32 against the cam 37 and thus coöperates with said cam in its action on the lay beam frame.

15 There will be two springs 41 employed, one at the inner side of each side frame of the loom, and these springs will correspondingly act against the vertical members 15 of the lay beam frame. The rear ends of the springs 41 are connected with eyebolts 42 which extend through laterally turned ears of brackets 43 secured to the side frames 10, and on each bolt 42 will be provided an adjusting nut 44 and lock or jam nut 45. By loosening the jam nut 45 the nut 44 may be rotated to draw the eyebolt 42 rearwardly or release it to move forwardly in a well-known mechanical manner, the purpose being to secure such adjustment of the tension of the springs 41 as may be desired. The forward ends of the springs 41 are connected by pivoted hooks 46 with the upper ends of the upper members 47 of bell crank levers 48 which are pivotally mounted on the side frames 10 and have their lower members 49 equipped with rollers 50 which are adapted to ride on the downwardly and forwardly inclined surfaces of the cams 19 20 which are secured to the vertical members 15 of the lay beam frame and constitute the only novel features connected with said members 15. The springs 41 are always under tension, and this tension is constantly exerted through the bell crank levers 48 to

move the lay beam frame forwardly to perform its beat, and said springs 41 are controlled in their action by the cam 27. The beat of the lay is caused by the springs 41, and hence the beat is cushioned. The 70 springs 41 may, however, only act when the cam 27 permits them so to do.

10 In the position of the several parts of the loom shown in Fig. 1, the lay is in its rear position and has been moved to that position against the stress of the springs 41 by the travel of the long arc surface 28 of the cam 27 against the roller 35 of the lever 32. When the lay beam frame is in its rear position the shuttle makes its throw, and during 80 this action of the shuttle the lay beam frame remains stationary and is held in stationary position by the cam 27, which cam at each of its movements comes to rest when in the position shown in Fig. 1 with one end of its 85 arc surface 28 at the roller 35. After the shuttle has made its throw the shaft 23 immediately commences to rotate and carries the arc surface 28 downwardly from the roller 35 and at this time the springs 41 by 90 acting on the bell crank levers 48 and members 15 of the lay beam frame, force said frame forwardly to perform the first beat, and this movement of the lay beam frame acts through the connecting rod 39 to 95 draw the lever 32 forwardly and carry the roller 35 into the recess or depression 30 of the cam 27, the cam thus permitting the springs 41 to make the first beat. Immediately upon the conclusion of the first beat 100 of the lay the projection 29 rides against the roller 35 and forces the lever 32 and connecting rod rearwardly in opposition to the stress of the springs 41 and thus returns the lay partly to its rear position. Immediately 105 after the projection 29 of the cam 27 rides by the roller 35, the springs 41 again act on the lay and through the same cause the roller 35 of the lever 32 to enter the recess or depression 31 of the cam 27, said recess 110 at such time permitting the lay to make its second or short beat. The continued rotation of the cam 27 carries the recess 31 away from the roller 35 and brings the projecting arc surface 28 of said cam against said 115 roller, and this has the effect of returning the lay to its rear position and of retaining the same in such position during the next throw of the shuttle. There is a momentary stoppage of the cam 27 at the end of 120 each of its rotations, the cam being then arrested while in the position shown in Fig. 1, and being so arrested to permit the shuttle to complete its throw, and thereupon the shaft 23 is automatically started in motion 125 according to usual methods in looms, and the cam 27 performs another rotation and the lay is permitted under the force of the springs 41 to perform its long and short beats.

The novel features of our invention reside in the springs 41 with their connections for causing the lay to perform its beats, and the cam 27 for controlling the action of the 5 springs 41 and moving the lay after its beat to its rear position and there holding it while the shuttle performs its duty, the shuttle being diagrammatically indicated at 51. While the lay is moving forwardly to 10 perform its beats the rollers 50 carried by the lower members of the bell crank levers 48 ride up the inclined surfaces of the cams 19, and upon the rearward motion of the lay said rollers ride down said inclined surfaces. We have found very great efficiency 15 in the employment of the bell crank levers 48 and cams 19 in connection with the springs 41 held under tension and acting against said levers.

20 What we claim as our invention and desire to secure by Letters Patent, is:

1. In a loom, in combination, a warp-beam, a cloth-beam, a lay and means for operating and controlling the movements of 25 the lay comprising springs secured at one end to the loom frame, pivoted levers supported from the sides of the loom-frame and to which the other ends of the springs are connected and which engage the lay to 30 force it forwardly, said springs being under tension, and a cam and connections therefrom to the lay for drawing the lay to its rear position and controlling the forward movements of the lay under the force of 35 said springs, said cam being rigid on a rotary shaft of the loom mechanism and having two recesses with a short projection between them and a comparatively long arc surface extending from one recess to the 40 other, and said connections from the said cam to the lay comprising a lever pivoted at its lower end below the horizontal plane of said cam and carrying a roller in engagement with said cam and a rod connecting the 45 upper end of said lever with the lower end of the lay.
2. In a loom, in combination, a warp-beam, a cloth-beam, a lay and means for operating and controlling the movements of 50 the lay comprising springs secured at one

end to the loom frame, pivoted two-armed levers supported from the sides of the loom-frame and to which the other ends of the springs are connected, cams on the side members of the lay engaged by the free ends 55 of said levers for forcing the lay forwardly, said springs being under tension, and means for drawing the lay to its rear position and controlling the forward movements of the lay under the force of said springs. 60

3. In a loom, in combination, a warp-beam, a cloth-beam, a lay and means for operating and controlling the movements of the lay comprising springs secured at one end to the loom frame, bell-crank levers 65 pivotedly supported from the sides of the loom frame and to which the other ends of said springs are connected, cams on the side members of the lay engaged by the free ends of said levers for forcing the lay forwardly, 70 said springs being under tension, and means for drawing the lay to its rear position and controlling the forward movements of the lay under the force of said springs.

4. In a loom, in combination, a warp-beam, a cloth-beam, a lay and means for operating and controlling the movements of the lay comprising springs secured at one end to the loom frame, bell-crank levers pivotedly supported from the sides of the 80 loom frame and to the upper members of which the forward ends of said springs are connected, cams on the side members of the lay having downwardly and forwardly inclined surfaces engaged by the lower members of said levers for forcing the lay forwardly, said springs being under tension, and means for moving the lay to its rear position and controlling the forward movements of the lay under the force of 85 said springs. 90

Signed at Belleville, in the county of Essex and State of New Jersey, this 7th day of March, 1916.
